UNITED STATES PATENT OFFICE.

HOSEA H. STRAIT, OF OVERLAND, MISSOURI.

QUOIN.

Application filed January 4, 1923. Serial No. 610,547.

This invention relates to quoins of the type used in locking up printing forms, and the principal object is to produce a simple quoin which may be used in restricted spaces.

Prior to this invention the quoins used in locking up printing forms were quite large and cumbersome, the most common form being composed of a pair of wedge-shaped members which cooperated with each other in such manner as to exert an outward pressure against the adjacent furniture within the chase. The quoins briefly described above functioned perfectly when the matter within the chase was so arranged that sufficient room was provided for the reception of said quoins, but this is not always so, as, for instance, where the locked matter includes a number of adjacent cuts which are separated by a very narrow space and which must be made movable for the purpose of registering, or where type matter is locked within a mortise and it is desired to locate the printed matter very close to the border. In these cases it was customary heretofore to lock the matter composing the form by wedging leads, or slugs, into these narrow spaces, but this method is a very unsatisfactory one as it is impossible to get the matter tight and "work ups" almost invariably result.

The quoin disclosed in the present application is intended to eliminate the annoyance occasioned by the failure of the unsatisfactory method described above, said quoin being so constructed as to be capable of being introduced into a very narrow space, a portion of said quoin being inserted into a recess formed in the adjacent matter, and when expanded said quoin will exert sufficient pressure against the matter within the chase to lock same securely therein.

A further advantage found in the use of the quoin disclosed herein results from the fact that a part of said quoin is reversible so that said quoin may be used where there is sufficient space, without necessitating the forming of recesses in the adjacent matter within the chase.

With the foregoing and other objects in view, the invention comprises the novel construction, combination and arrangement of parts hereinafter more specifically described and illustrated in the accompanying drawings, wherein is shown the preferred embodiment of the invention. However, it is to be

understood that the invention comprehends changes, variations and modifications which come within the scope of the claim hereunto appended.

Fig. I is a plan view of a chase showing a plurality of cuts locked therein by my improved quoins, one of said cuts being broken away to show the manner of inserting the quoins therein.

Fig. II is an enlarged front elevation of my improved quoin.

Fig. III is an enlarged vertical section through the quoin shown in Fig. II.

Fig. IV is an enlarged vertical section similar to Fig. III but showing a part of the quoin reversed so that said quoin may be used where space will permit without necessitating the boring of holes in cuts or other matter within the chase.

Fig. V is a view showing the manner of using my quoin to lock type matter within a mortise.

Fig. VI is a view showing the tool used in expanding or contracting my quoin.

In the drawing, A designates a chase which may be of the type usually employed by printers. To illustrate the use of my improved quoin, I have located a plurality of cuts B within the chase A, and to partially fill the space between the cuts B and the ends of the chase A I employ the usual strips of furniture C.

Q designates my improved quoins, each of which comprises a non-rotatable member 1 and a rotatable member 2. The member 1 comprises a plate portion 3 and an integral portion 4 extending outwardly from said plate portion 3. The portion 4 is provided with a central internally threaded aperture 5 for a purpose to be hereinafter described. The member 2 comprises a disk portion 6 provided with notches 6' and a centrally located shank 7 preferably formed integral with said disk portion 6.

Formed on the plate portion 3 of the member 1 adjacent to the upper edge thereof is a pair of integral prongs 8, said prongs being extended from said plate portion 3 in the same direction that the portion 4 extends from said plate portion, and formed on said plate portion 3 adjacent to the lower edge thereof is a similar pair of prongs 9 which extend from the side of the plate portion 3 opposite to the side from which the prongs 8 extend. In use the threaded shank 7 of the member 2 extends into and engages the threads in the

aperture 5 in the portion 4 of the member 1 as shown in Figs. III and IV of the drawings, and it is apparent that the distance between the plate portion 3 of the member 1 and the disk portion 6 of the member 2 may be increased or diminished by rotating the member 2.

The use of my improved quoin will now be explained in connection with Fig. I of the drawing. As will be observed, the spaces between the cuts B are very narrow and it is, of course, necessary to use the quoins arranged as shown in Fig. III. To permit this, the wood backings of the cuts B are provided with recesses B' sufficient in diameter and depth to receive the portions 4 of the stationary members 1 of the quoins. The portions 4 are inserted into the recesses B' and the prongs 8 are driven into the wood adjacent to said recesses whereby said members 2 are prevented from turning. When the parts are in the positions shown and described, the disk portion 6 of each of the members 2 bears against an adjacent cut B and two cuts separated by any one of the quoins may be moved away from each other by rotating the member 2 in a direction to cause the threaded shanks 7 to move outwardly in the threaded aperture 5.

The quoins Q' in Fig. I are used with the parts in the positions illustrated in Fig. IV. When arranged in the manner illustrated the prongs 9 of the member 1 are driven into the wood backing of a cut or into a piece of furniture whereby said member 1 is held immovable, and as the distance between the plate portion 3 of the member 1 and the disk portion 6 of the member 2 is increased thereby the interposition of the portion 4 therebetween the quoins may be used in much wider spaces than would be possible with the quoin parts used as shown in Fig. III, and also said quoins may be used as illus-

trated in Fig. IV without the necessity of forming recesses in the cuts or other matter within the chase, the prongs 9 holding the member 1 in a fixed position preparatory to the locking of the matter within said chase or while said matter is being adjusted.

To provide a means for conveniently rotating the disk portion 6 of the member 2, I provide a tool 10 which is provided with a projection 11 adapted to be inserted into the notches 6' in said disk portion and an arcuate face 12 which contacts with the periphery of said disk portion.

Fig. V shows two ways in which my improved quoins may be used to lock matter within a mortise.

The use of the quoin disclosed in the present application provides means whereby cuts or other matter within a chase may be moved in any direction when arranged as shown in Fig. I. This is an important feature in connection with multicolor jobs where it is necessary to locate parts of one cut in registration with parts of other cuts. It is apparent from Fig. I that any cut may be moved by screwing or unscrewing the various quoins without loosening the form.

I claim:

A quoin consisting of two parts comprising a plate provided with an integrally formed internally threaded hub portion projecting therefrom, and another plate adapted to be operatively associated with said first named plate, said second named plate being provided with a threaded shank rigidly affixed thereto, and said second named plate being also provided with means whereby said threaded shank may be rotated within said hub on said first named plate.

In testimony that I claim the foregoing I hereunto affix my signature.

HOSEA H. STRAIT.
